UNITED STATES PATENT OFFICE.

GUSTAV A. FISCHER, OF CLEVELAND, OHIO.

PASTEURIZING-MACHINE.

1,093,924.

Specification of Letters Patent. Patented Apr. 21, 1914.

Application filed November 30, 1912. Serial No. 734,259.

To all whom it may concern:

Be it known that I, GUSTAV A. FISCHER, a citizen of the United States, residing at Cleveland, in the county of Cuyahoga and State of Ohio, have invented a new and useful Improvement in Pasteurizing-Machines, of which the following is a specification, the principle of the invention being herein explained and the best mode in which I have 10 contemplated applying that principle, so as to distinguish it from other inventions.

This inventive conception relates, as regards its principal adaption, to a pasteurizing machine. The assembled structure with 15 its specific improving features lends itself however to alternative functions in a closely allied art.

Accordingly, the object of the invention, while primarily to provide a feasible combination of elements which will measurably increase the pasteurizing efficiency now attained, is also to provide a machine capable of fulfilling different uses and moreover exercising each in coöperation with the distinct 25 agencies and facilities that may be at hand.

The said invention consists of means which are hereinafter described and particularly pointed out in the claims.

The annexed drawing and the following 30 description set forth in detail certain means embodying my invention, the disclosed means, however, constituting but one of various mechanical forms in which the principle of my invention may be applied.

Figure I is a vertical axial section of a machine in which the principle of my invention is incorporated, certain parts being seen in elevation. Fig. II is a part section, part end view on line II-II of Fig. I looking in the direction of the arrows. Fig. III is a section on line III-III of Fig. I looking in a similar direction.

The structural elements of my machine are, in logical order, an upright casing comprising two lateral supporting standards 1 and end members 2. These end members 2 are of annular formation and moreover of angular cross-section to present two substantially horizontally extending annular 45 flanges 3 extending toward each other, as clearly seen in Fig. I. The outward portion of the interior annular surfaces of each of the flanges 3 is fashioned with an annular depression 4 likewise best represented in 50 Fig. I. Surrounding the end members 2 is

an inclosing member 5 which is also of angular cross-section so as to involve the two annular flanges 6 at opposite ends thereof. The member 5 is secured to the member 2 through the medium of a suitable number 60 of screws 7. In turn surrounding the member 5 and spaced a distance therefrom corresponding with the extent of outward projection of the flanges 6 is an arched hood 8. It may be secured thereto in any approved 65 manner, such as by soldering. The hood 8 is provided centrally with a stack 9. Underneath near the base of the standards 1 and extending substantially therebetween are a pair of gas burners 10. The construction should be understood to permit the substitution of a fire-box for these burners if desired or if gas facilities are not at hand.

Disposed in a substantially horizontal position so as to extend through the openings 75 in both of the members 2 and project some distance beyond each is a pasteurizing cylinder proper 11. This cylinder is preferably of copper with open ends and is provided near each end with an iron collar 12 80 adapted to lie contiguous with the inwardly disposed annular surfaces of the flanges 3. In this location with respect to the annular depressions 4 a common type of stuffing-box 13 is formed, whereby a water-tight relation 85 may be established between the members 2 and the surface of the cylinder 11 through the medium of the usual packing glands 14 and packing 15 satisfactorily held in place through the medium of screw threaded studs 90 16 and nuts 17. Fixedly secured around opposite extremities of the surface of the cylinder 11 are a pair of gears 18 adapted to mesh respectively with a pair of driving pinions 19, in turn fixed through the medium of 95 keys 20 to a driving shaft 21 connected with a source of power.

From so much of the description it will be readily understood how a rotation on the part of the shaft 21 is transmitted to a 100 similar motion on the part of the cylinder 11. The direction of rotation of this cylinder is indicated by arrows in Figs. II and III. It should be noted here that one end of the cylinder 11 is flared as designated by 105 the reference numeral 22 in Fig. I, whereas the opposite end tapers as designated by the numeral 23 in the same figure. As will now be manifest by those familiar with this particular art, a closed jacket surrounding an 110

intermediary portion of the cylinder 11 is provided. This is in fact intended as a water or steam jacket and is provided with a water inlet 24, water overflow outlet 25, 5 steam inlet pipe 26 provided with a plurality of perforations 27 extending substantially thereacross, and hand-hole 28 for inspection or cleansing purposes and finally a conventional type of gage 29. Surrounding 10 this water or steam jacket is an inclosing flue passage establishing communication between the heating means below and the stack 9.

A pipe 30 extends through the inlet end 15 of the cylinder 11, which is in fact that end which is tapered, and is adapted to supply the fluid in uniform and regulated quantity to the bottom of the cylinder. Supported in any practical manner below the opposite 20 site flared end of the cylinder is a receiving funnel 31 adapted to receive the now pasteurized fluid. Fastened to and extending outwardly from each of the members 2 laterally of their vertical planes is a bracket 25 32. These brackets are adapted to support a clamping member 33 which extends on an incline through the cylinder 11 as clearly represented in Fig. I. The relative position of this member 33 is furthermore on the same side with respect to the cylinder as the brackets 32 and this particular side of the cylinder is moreover the downwardly moving side as again indicated by the arrows 30 in Figs. II and III. This clamping member is curved at its lower end 34 which is adjacent the funnel 31 while its upper end 35 is similarly bent downwardly adjacent the supply pipe 30. The precise position assumed by this member 33 interiorly of 35 the cylinder is preferably inclined as already stated and specifically from the lower outlet end upwardly so as to barely intersect the horizontal plane of the axis of the cylinder. Along substantially that much of its length 40 45 as is disposed within the cylinder 11, the member 33 is slotted, and it is within such slot that any suitable type of wiper 36 is intended to be removably secured through the instrumentality of the transverse openings 37 and thumb screws 38. The proximity of the clamping member 33 with respect to the lower quadrant of the cylinder surface is such that the wiper secured to it 50 55 may have sufficiently strong contact.

The operation of my machine may be thus described: Assuming the water within the jacket to have become sufficiently heated either through the means of the firebox or gas burner outside, or the steam pipe 26 inside thereof; and rotation to have been imparted to the cylinder in the direction shown, the fluid to be pasteurized may be supplied preferably by means of a pump through the pipe 30. Thereupon the latter 60 65 is carried upwardly upon the interior prop-

erly heated surface of the cylinder. On account of the adhesive tendency of most of the fluids which are subjected to the pasteurizing operation, such fluid will be carried around as a film or sheet beyond the top of the cylinder and half again as far or until it is wiped off by the wiper 36 at its specific point of contact therewith. The slope of the wiping contrivance in the meantime insures the downward travel of the liquid in the direction of the funnel 31. Especial cognizance should be taken of the fact that my arrangement of the several parts compels the fluid under treatment to travel a nearly maximum extent upon the interior surface of the cylinder. 70 75 80

Having now fully described my invention, what I claim and desire to secure by Letters Patent is:

1. In a machine of the character described the combination of a cylinder provided at each end with an opening, distinct means for rotating and heating said cylinder, means for supplying the fluid to be treated to the interior of said cylinder, and a wiper projecting into said cylinder and having inclined lineal contact therewith. 85
2. In a machine of the character described the combination of a cylinder having open ends, distinct means for rotating and heating said cylinder, means for supplying the fluid to be treated to the interior of said cylinder, and a stationary wiper extending through said cylinder and contacting the lower downwardly moving quadrant thereof. 95
3. In a machine of the character described the combination of a substantially horizontal cylinder having open ends, one such end tapering and the other being flared, distinct means for rotating and heating said cylinder, a member extending between opposite ends, and a wiper removably secured to said member and adapted to contact said cylinder. 100
4. In a machine of the character described the combination of a cylinder provided at opposite ends respectively with an inlet and an outlet opening, distinct means for rotating and heating said cylinder, and a wiper projecting through and contacting the interior surface of the latter, said wiper being downwardly inclined away from said inlet. 110
5. In a machine of the character described the combination of a substantially horizontal cylinder having opposite end openings, means for rotating said cylinder, a water container surrounding said cylinder intermediately of its ends, and means for heating the water in said container. 120
6. In a machine of the character described the combination of a frame, a cylinder supported thereon and having opposite end openings, means for rotating said cylinder, a water container surrounding said cylinder intermediately of its ends, means for heating 125 130

the water in said container, a bracket af-
fixed to said frame and extending through
said cylinder, and a wiper secured to said
bracket and contacting the interior surface
5 of said cylinder.

7. In a machine of the character described
the combination of a frame, a hollow mem-
ber mounted thereon and having open ends,
distinct means for rotating and heating said

member, and a wiper supported by said 10
frame and extending through said member.

Signed by me, this 29th day of Novem-
ber, 1912.

GUSTAV A. FISCHER.
